LAUNDRY MACHINE

James B. Kirby, West Richfield, Ohio, assignor,
by mesne assignments, to The Apex Electrical
Manufacturing Company, Cleveland, Ohio, a
corporation of Ohio, as trustee

Application October 29, 1932, Serial No. 640,252

6 Claims. (Cl. 68—15)

This invention relates to laundry machines and in particular laundry machines of the type wherein both washing and extracting operations are performed.

5 One of the objects of this invention is to provide a generally simplified form of mechanism for operating a combined washer and extractor; the mechanism being arranged so as to perform the washing and extracting operations with a 10 high degree of efficiency and with the consumption of a small amount of power.

Another object of this invention is to provide in a machine of the type defined, a new form of gearing whereby the customary gear cases are 15 eliminated and a relatively inexpensive form of unhoisted gearing is substituted in their place. By this improvement lubrication difficulties and oil leakage problems are eliminated.

Another object of this invention is to provide 20 in a machine of the type defined, a driving mechanism in which the speed reducing steps and the driving of the various elements of the operating mechanism are accomplished by belt-driven means, thus providing a quiet and efficiently 25 driven mechanism.

Another object of this invention is to provide 30 in a machine of the type defined, an improved means for the handling and the disposal of the water used in the washing and extracting operations, whereby the machine may be operated in a 35 convenient manner.

Another object of this invention is to provide 40 in a machine of the type defined, an improved form of belt adjustment whereby a single member takes care of the adjustment of a plurality of belts.

Another object of this invention is to provide 45 in a washing machine, an improved agitator and agitator operating mechanism whereby the liquid contents of the machine are circulated in a turbulent manner.

Another object of this invention is to provide 50 in a machine of the type defined, an improved and simplified form of control mechanism for the washer and extractor operating mechanisms, whereby such control can be effected in an easy and convenient manner.

A further object of this invention is to provide 55 in a machine of the type defined, an improved arrangement of driving and operating mechanism wherein all of the rotating parts of the machine rotate about vertical axes, whereby power losses are reduced and the efficiency of the machine is raised to a high degree.

55 Stated in general terms my invention consists

in the provision of a two-tub combined washing and extracting machine wherein such tubs are supported by a suitable frame beneath which is carried a driving motor having belt-transmission means for driving a centrifuge, a pump and a 5 rotating and gyrating agitator. Suitable control means are provided for selectively controlling the operation of the washing and extracting mechanism. A compensating idler pulley is provided for effecting the adjustment of the belts and hose 10 receiving apertures are provided in the top of the machine for directing liquid discharged from the pump to either the washing compartment or to a drain.

With these and other objects in view, the invention consists in the novel construction, arrangement and combination of parts, hereinafter illustrated and described and some of its embodiments in the accompanying drawings, and particularly pointed out in the appended claims. 15

Referring to the drawings: Figure 1 is a side elevational view, partly in section, of my improved clothes washing and extracting machine.

Figure 2 is a plan elevational view of the top of the machine illustrated in Figure 1. 20

Figure 3 is an enlarged sectional view taken on line 3—3 of Figure 2 showing the details of the agitator mechanism.

Figure 4 is a sectional view taken on line 4—4 of Figure 3 showing certain details of the clutch. 30

Figure 5 is a detail view of the washer mechanism clutch showing the clutch parts in position to drive the washing machine agitator.

Figure 6 is a plan view of the underside of the machine shown in Figure 1. 35

Figure 7 is an enlarged sectional view taken on line 7—7 of Figure 2, showing certain details of the fluid handling means.

Figure 8 is an enlarged sectional view taken on line 8—8 of Figure 6, illustrating the details 40 of the belt adjustment.

Figure 9 is a plan view of a modified form of agitator and driving mechanism; and

Figure 10 is a sectional view taken on line 10—10 of Figure 9. 45

In Figure 1, I have illustrated a form of my invention as applied to a two-tub washing and extracting machine. The machine illustrated comprises a washer tub or casing 1 and an extractor tub or casing 2. These elements of the machine are carried on a suitable frame or base member 3, supported by legs 4 having casters 5, provided for the purpose of facilitating the moving of the machine. The washer tub is secured to the frame member 3 by means of a number 55

of bolts 6 circumferentially spaced about the bottom of the tub at points adjacent to the outer edge thereof. The extractor casing 2 is secured to the base 3 in a similar manner by means of 5 bolts 7. The extractor casing 2 is provided with an apertured top-plate 8 which provides a clothes chute as between the adjoining parts of the tub 1 and casing 2. The plate 8 is fitted snugly over the top of the casing 2 and is secured to the tub 1 by the bolts 9. Within the extractor casing 2 there is provided a rotatable container 10 having perforations 11 whereby adherent water may be removed from fabric articles during the centrifugal extracting operation.

15 An agitating device comprising a base-member 12 of spherical contour and having vanes 13, is provided for agitating the liquid contents of the washer tub or casing 1. The base-member 12 is closely fitted over a hollow shield 14 of spherical 20 contour within which certain parts of the driving mechanism for the agitating member are housed. The agitating device is driven with a combined gyratory and rotational movement. The driving of the agitator is effected through a rotatable 25 agitator-driving shaft 15 to which is rigidly affixed a bracket 16 carrying an angular crank 17 which is in the form of a stub shaft fixedly secured to the bracket 16.

The bracket 16 is preferably in the form of a 30 die casting and is cast about the shafts 15 and 17 so that these three elements form an integral unit. The base-member 12 is provided with a central bearing portion 18 within which the shaft 17 is rotatably journaled. The base-member 12 35 is secured in place on the shaft 17 by means of a washer 19 and a screw 20, the screw engaging the shaft 17 and the washer 19 overlapping and engaging the countersunk central portion of the member 12.

40 A gear 21 is secured in threaded engagement to the underside of the base-member 12 in alignment with the axis of this member. The gear 21 meshes with a fixed or stationary internal gear 22 threadably secured to the bearing member 23 of the shaft 15. The outer edge of the internal gear is extended in the form of an annular plate 24 and it carries at its outer edge the spherical shield member 14. The bearing member 23 cooperates with the internal gear 22 and with suitable gaskets 25 in sealing the opening provided in the bottom of the tub 1 for the reception of the agitator driving mechanism.

An electric motor 26 is provided to drive the 55 washing and extracting mechanism. A belt 27 provides a direct driving connection between the motor and the extractor container 10, the pump 28 and the adjustable idler pulley 29. The idler pulley carries a small pulley 30 for driving a second belt 31, which in turn serves to drive an enlarged pulley 32 for driving the washing mechanism.

The washing and extracting mechanisms are 65 provided with suitable clutches whereby these parts of the machine may be connected or disconnected selectively in driving relation to the electric motor. The pump 28 is continuously driven, having at its inlet side an open communicating connection 33 with the extractor casing 2 and a valve-controlled communicating connection 34 with the washer tub. The outlet side of the pump is connected in communicating relation with one end of a hose 35 which terminates at its other end in a swiveled gooseneck 36.

The washing mechanism is controlled by means 70 of the clutch illustrated in Figures 3, 4, and 5.

This clutch is of the friction cone type and it has a driving cone 37, the outer edge of which is fixedly secured to the enlarged driving pulley 32 and the center of which is formed with a bearing surface. The cone 37 is rotatably mounted on a 5 bushing 38. A driven conical clutch member 39, faced with a suitable friction material 40, cooperates with the driving clutch member 37 in controlling operation of the agitator shaft. The driven clutch member 39 is fixedly secured to the 10 shaft 15 by means of a set screw 41, which passes through a slot 42 formed in the bushing 38.

The lower end of the bushing 38 is formed with a shoulder or collar 43. A cup-shaped member 44 having a flanged rim is secured by any suitable 15 means such as the screw 45 to the lower end of the shaft 15. A coil spring 46 is held in compression between the cup-shaped member 44 and a washer 47 which abuts against the shoulder 43 of the bushing 38. The upper end of the bushing 20 38 abuts against a washer 48. The washer 48 in turn is pressed against the lower end of a sleeve 49 and is held in such position by reason of the force exerted by the spring 46.

A slanting slot 50 is formed in the sleeve 49 for 25 receiving a bolt or stud 51 fixedly carried by the bearing member 23. An operating handle 52 is fixed to the sleeve 49. When the operating handle 52 is angularly shifted in one direction or the other the inclined slot 50, working on the bolt 30 51 serves to raise or lower the sleeve member 49 and in doing so it axially shifts the bushing 38 and the driving clutch member 37, thus connecting or disconnecting the clutch members 37 and 39 with each other as the case may be. This arrangement provides a simple and inexpensive 35 form of clutch device.

Suitable packing means 54 are provided in the centrally enlarged lower portion 53 of the bearing member 23. The packing material 54 carried at 40 this point is pressed in sealing relation about the shaft 15 by means of a slidably fitted gland 55 and a spring 56, the latter being pressed against the gland by means of an apertured nut 57 threadedly engaging the lowermost end of the bearing 45 member 23.

In Figure 3 the clutch is shown in its disengaged position and in Figure 5 the clutch is shown in its 50 engaged or driving position. In such positions of the clutch and the sleeve 49, the stud 51 is received in one or the other of the horizontal end portions of the slanting slot 50. When the clutch is in the position shown in Figure 5 and the motor is operating, the shaft 15 and the angular crank 17 are continuously rotated in one direction 55 thereby causing the agitating member 12 to gyrate about the axis of the shaft 15 after the manner of a gyrostatic pendulum or a spinning top having the tip of its peg in a conical hole. The center of the agitating member thus describes a circular path in a direction corresponding to the direction of rotation of the shaft 15. Due to the fact that the internal gear 22 is larger than the gear 21, a rotational movement of greater angular velocity and reversely to that of the shaft 15 is imparted to the agitating member 12. The motion of the vanes or blades 13 of the agitator thus is the resultant of the two circular motions or compound movement of the agitator.

The speed of rotation of the agitating member as compared with that of the shaft 15 may be decreased by either making the internal gear 22 smaller or by increasing the size of the external gear 21 and similarly if it is desired to 75

prevent any rotational movement of the member 12 about its own axis, the gears 21 and 22 would be both of the same size. Thus by varying the relative size of the gears 21 and 22 the agitator 5 can be made to rotate faster or slower about its axis or such relative rotational movement may be suppressed entirely if so desired.

With the parts as shown, the base-member 12 is driven with a gyratory motion in one direction 10 about the axis of the shaft 15 and with a rotational motion in a reverse direction about the axis of the angular crank 17. Due to the compound motion imparted to this member the blades 13 of the agitator will sweep back and forth about 15 the central region of the tub in such manner so as to cause a violently pulsating circulation of the water upwardly from the center of the tub and then outwardly and downwardly and then inwardly back to the agitator with a movement 20 similar to that described by the particles of a circular vortex ring about the axis of the vortex filament.

The washing action accomplished by my improved form of agitator is somewhat similar 25 though in a reverse direction to that accomplished by the reversely rotating so-called gyrator type of washing machine with the difference, however, that such machines require complicated and power-consuming reversing mechanism, 30 whereas the same object is accomplished in my improved construction by the combination of the gyratory and rotary motions imparted to the agitating member. By reason of this arrangement the machine operates very smoothly and 35 quietly and requires considerably less power to operate than would be necessary if some of the parts were reciprocated or alternately-reversely operated.

A clutch member 58 of similar construction 40 to the washer mechanism clutch just described is provided for controlling the operation of the extractor container 10. A suitable control handle 59 is provided for effecting the engagement and disengagement of this clutch. The pump 45 28 is provided with a suitable control valve having an operating handle 60 for connecting and disconnecting the pump to the washer tub. As previously stated the pump is in continuous communication with the extractor tub 2 and the outlet side of the pump is in constant communication 50 with the hose 35.

The gooseneck 36 of the hose 35 is arranged for 55 reception in either of the openings 61 or 62 formed in a recess in the top of the extractor top plate 8. The opening 61 communicates with a drain hose 63, whereas the opening 62 communicates with a side opening 64 formed in the upper part of the wall of the washer tub. By this simple expedient the water drained from either 60 the washer tub or the extractor tub can be directed to a suitable drain or returned to the washer tub. This arrangement provides a very convenient method of handling waste water from the machine or for returning usable soapy water 65 from the extractor casing to the washer tub and it at the same time prevents spilling and splashing water about the floor in the room where the machine is used as the hose 63 empties into a suitable drain or receptacle.

70 The idler pulley 29 is slidably mounted upon a plate 65 and is secured thereto by means of a lower and an upper plate 66 and 67 secured together by means of a rivet 68 which is slidably fitted in a slot 69 formed in the plate 65. The 75 plate 66 has secured to it a stub shaft 70, which

provides a bearing pin for the idler pulley. The plate member 67 is provided with an apertured up-turned portion 71 through which an adjusting rod 72 extends.

The rod 72 is threaded at its opposite end and 5 is adjustably received in a threaded member 73 swiveled on the plate 65. A spring 74 abuts against the plate member 71 at one end and at its other end it engages a washer 75 carried by the rod 72. A knurled operating handle 76 is 10 provided on the end of this rod for tightening or loosening the tension of the spring 74 and in this manner tightening and loosening the tension of the belts 27 and 31. The plate 66 is freely 15 movable about the rivet 68 and this arrangement permits sufficient oscillation of the pulley about such point so as to equalize the tension between the belts 31 and 27. The plate 65 also serves as a support for the motor 26 which is secured thereto by studs 84. 20

In the modified form of agitating mechanism shown in Figures 9 and 10 the agitator member 11 is rotatably mounted upon a vertical crank 78 fixed to turn with an agitator drive shaft 79. The agitating member 11 is provided with a plurality of vanes 80 and it has a base member 81, the same being in the shape of a hollow inverted dished member which serves to provide a support for a gear 82 operatively associated with an internal stationary gear 83. 30

This arrangement operates in much the same manner as does the mechanism shown in Figure 1 with the difference, however, that the agitator gyrates in a horizontal plane as will be evident from a consideration of the drawings. Thus 35 when the shaft 79 is rotated the agitator is gyrated about an axis of the shaft 79 and at the same time by reason of the relative size of the gears 82 and 83 it is given a rotational motion in a direction reverse to the direction of 40 its gyratory movement.

The operation of the machine is a very simple matter. To begin with the tub 1 is filled with clothes and a detergent liquid or soap solution. The control lever 52 is shifted to the "on" position after the motor 26 has been started and after a few minutes of agitation the operation of the agitator is stopped, and the clothes are transferred to the extractor casing 10. The extractor control lever 59 is then moved to the "on" 45 position and in a short time the centrifuge will have extracted most of the water from the clothes whereupon the centrifuge is stopped and the clothes removed therefrom. 50

The clothes are next rinsed either by adding 55 clean water to the extractor while stationary or rotating or by transferring them to a tub full of rinsing water after which operation the clothes are returned to the extractor for the final drying operation. During the initial extracting operation the soapy water can be returned to the tub 1 by connecting the gooseneck 36 to the hole 62 and during the second extracting operation the rinse water can be conveyed to a drain by connecting the gooseneck to the hole 61. When the 60 washing is finished the valve member 60 is shifted to open valve position and contents of the tub 1 are pumped to a drain. 65

Furthermore it is to be understood that the 70 particular forms of apparatus shown and described, and the particular procedure set forth are presented for purposes of explanation and that various modifications of said apparatus and procedure can be made without departing from my invention as described in the appended claims. 75

Having thus described my invention what I claim is:

1. In a washing machine, a tub for containing water and goods to be washed, an agitator mounted for gyratory movement in said tub near the bottom thereof and having a plurality of upstanding water impelling blades extending outwardly therefrom in contact with the goods and water in said tub, said blades being of substantial height near the center thereof and decreasing in height towards the ends thereof whereby side faces of substantial area are provided and while the agitator is operated the water and goods will be forced upwardly, outwardly, downwardly and then inwardly in circulatory paths to violently force the water through, between and around the goods and thoroughly cleans them while they are sustained in the water and contacted with by the impelling blades of said agitator, and motor driven means for revolving and rotating said agitator.

2. In a washing machine, a container for detergent liquid and articles to be washed, an agitator mounted in said container for both bodily and rotational movement and power means for continuously driving the agitator, said agitator consisting of a base member and a plurality of liquid impelling vanes extending from one face thereof, said vanes being of maximum depth adjacent the center thereof and having their outer ends inclined toward and merging in the base member, the central portion of said base member being free from water impelling projections.

3. A clothes washing machine comprising a fabric and liquid containing receptacle and a supporting frame, a vertical shaft mounted centrally of said receptacle and having an oblique crank portion at the free end, a clothes agitator immersed in the contents of said receptacle and

mounted on said crank portion, said agitator comprising a base with upstanding vanes, a source of power operatively associated with said shaft, and means acting simultaneously to gyrate and rotate said agitator when said shaft is rotated by said source of power.

4. A clothes washing machine comprising a fabric and liquid containing receptacle and a supporting frame, a vertical shaft mounted centrally of said receptacle and having an oblique crank portion at the free end, a clothes agitator immersed in the contents of said receptacle and mounted on said crank portion, said agitator comprising a base with upstanding vanes, a source of power operatively associated with said shaft, and means acting simultaneously to gyrate such agitator in one direction and to rotate it in a reverse direction when said shaft is driven by said source of power.

5. In a clothes washing machine, gyrating mechanism comprising a driven shaft, an angular crank on said shaft, an agitator having a spherically shaped base with upstanding flanges rotatably mounted on said crank and differential means giving said agitating member a rotational movement relatively to the movement of said angular crank.

6. A clothes washing machine comprising a tub having a housing adjacent to the center at its bottom, said housing having an inturned side wall projecting above the bottom of said tub and providing a housing for motion-converting mechanism, a hollow shell receiving said housing and mounted for gyratory movement relatively thereto, vaned agitating means carried by said shell, and a shaft in said housing having a crank journaled to said shell for driving it with a gyratory movement.

JAMES B. KIRBY.
